UNITED STATES PATENT OFFICE.

HOMER M. BARBER, OF GOLDFIELD, NEVADA.

SET FOR TIMBERING MINES.

1,226,444.

Specification of Letters Patent. Patented May 15, 1917.

Application filed May 1, 1916. Serial No. 94,606.

To all whom it may concern:

Be it known that I, HOMER M. BARBER, a citizen of the United States, residing at Goldfield, in the county of Esmeralda, State 5 of Nevada, have invented new and useful Improvements in Sets for Timbering Mines, of which the following is a specification.

This invention relates to a set for timbering mines, and it is part of a system used for 10 the mining of ore by a slicing method. The slicing method as heretofore practised consists in driving in from the working shaft on the first level below the capping usually about one hundred feet until the ore is 15 countered. A level is then driven through the center of the ore body raising at intervals to the capping. The upraises are usually spaced about fifty feet. From the top of the first raise to the top of the second raise, immediately below the capping the ore is 20 stopped out, thus forming a slice. Timbers are placed in position as the ore is removed. Upon completion of the removal of the ore 25 the capping is caved in. This is done by blasting, whereby the caved capping or waste covers the timbers.

Another method comprises filling the 30 stope with waste. Such systems result in the loss of all the timber. The system of slicing has the advantage of avoiding filling the open space made by the removal of ore with waste from distant places.

My improved set for timbering permits a 35 change in the method of taking out the ore and putting in the timbers. Instead of taking the whole slice before caving, the caving may be done as the miners retreat. A level is driven in from the working shaft to the ore and upraises driven as before. From the 40 top of the first raise a tunnel is driven to the second raise, and at the same time transversely from the foot wall to the hanging wall. The ore is then taken out progressively toward the second raise, timbers being 45 put in as the ore is taken out and the blocks from which ore is removed caved in as the miners retreat toward the second raise. The timbers which are reclaimed from the sets are used to timber the next sets opened up 50 by the removal of the ore.

The important feature of my invention is the post construction whereby the sets may be quickly and easily removed when caving.

I have illustrated an embodiment of my invention in the accompanying drawings, in 55 which:

Figure 1 is a view of a set in position.

Fig. 2 is a post of the set.

Fig. 3 is a section as seen on the line 3-3 of Fig. 2.

Fig. 4 is a section as seen on the line 4-4 of Fig. 2.

Fig. 5 is an enlarged fragmentary view showing a shackle as applied to a post.

Fig. 6 is a plan view of the shackle applied to a post.

More specifically, 7, 8, and 9 indicate posts of similar construction. 10 and 11 are caps resting upon the upper ends of the posts and braced by braces 12, 13, 14 and 15. Ties 16 70 and 17, and an intermediate tie, not shown, resting on post 8 space the sets. On top of the capping is bridging indicated generally by 18 and supporting timber matting 19. which carries the weight of the roof. 75

The posts 7, 8, and 9 are each similar in construction. Referring to Figs. 1, 2, 3 and 4, each post is comprised of two sections, an upper section 20 and a lower section 21.

The posts are preferably square or rectangular in section, and in actual practice are preferably 7 feet long and 8x8 inches. About two feet from the top of the post a cut 80 22 is made transverse to the post dividing it into two parts. This cut is made at an angle 85 preferably of 14 degrees and 30 minutes to the horizontal. In order to prevent separation of the two parts when a post is supporting weight, I have provided a hole extending across the cut and divided diametrically 90 by the cut. This hole is denoted by 23 and forms registering mortises, one in each half 95 of the post. The hole is preferably bored before the cut is made, and if made 1.34 inches in diameter, it will receive a one inch standard pipe which is split longitudinally into halves, each half being fastened to a section of the post by means of wood screws or other suitable fastening means. A pin is inserted in the hole and is preferably made 100 of machine steel, and of the same diameter as the hole, which, according to the dimensions above referred to would be one inch.

With the pin in place forming a tongue the post will support loads parallel to its 105 axis without the sections of the post slipping.

ping. It is obvious that removal of the pin 24 will permit the post sections to slip and the set to collapse.

5 Bearing lags commonly known as scabs are placed upon each side of the post and extend from the bottom of the post to a point adjacent the cut. The scabs are indicated by 25, 26, 27 and 28. With the dimensions of the post above referred to the scabs would 10 preferably be one inch by 6 inches by 5 feet long, and are fastened to the post by nailing or other suitable means. These scabs support the toes of the braces 12, 13, 14 and 15, whose positions are shown in the completed set.

15 In erecting the sets the lower sections 21 of the posts are set on foot blocks, the pins 24 are then placed in position in the mortise 23 and the upper section 20 of the post set in 20 place. Shackles are then clamped to the post to hold the upper and lower sections together. In Figs. 5 and 6 are shown a shackle 29 of a common form, comprising a section 30 which embraces one half of the 25 post provided at the ends with hinged portions 31 and 32 having outstanding locking fingers 33 and 34. To the locking fingers 33 is pivotally connected a loop 35 having an arm 36 pivotally connected thereto intermediate its ends. The toe 37 of the arm 36 is engaged with the finger 34 and the arm is forced against the section 31 of the shackle thereby drawing the sections 31 and 32 together and locking them. As the upper 30 section 20 of the post is not provided with scabs, shims 38, 39, 40 and 41 are inserted between the shackle and the upper section of the post. These shims are of the same cross sectional dimensions as the scabs.

40 Assuming that the sections 20 and 21 of the posts have been shackled together, the caps 10 and 11 and the ties placed in position and where desirable the bridging 18 placed thereon. The use of bridging allows the 45 caps to swing freely when the set is collapsed. The posts 7, 8, and 9 are then plumbed and the whole blocked down. The shackles may then be removed and the braces 12, 13, 14 and 15 set in position, the 50 toe of a brace rests upon a scab and extends to the center of a cap. Wedges are driven in the space between the toes of adjacent braces from each side, thus tightening them and at the same time permitting easy removal when caving. The wedges are indicated by 42 in Fig. 1.

The set is collapsed by taking out the braces and the pin and then tapping the post. With my improved system of slicing 60 the weight upon the timbers is never great, which permits them to be taken out easily.

and gives ample time to reclaim the timbers. The timber mat 19 is the only portion which is lost. As large portions of the slice are never open at one time, accidental caving 65 which endangers the life of men is reduced to a minimum.

The raise sets are cut similar to the stope sets and braced horizontally instead of at an angle. The construction of particular 70 sets may be varied, but in general the sets are similar to the square sets now in common use. With my improved set the post has no horn and is braced from all sides.

What I claim is:

75 1. A set, comprising a combination of posts divided transversely by an oblique cut and having registering mortises in the faces of said cut, detachable tongues disposed in said mortises, transverse shoulders on said posts below the division, a cap disposed on and between said posts, and braces each having a toe disposed on one of said shoulders and the other toe disposed against said cap, said braces overlaying the cut in said 80 post, thereby preventing slipping of the same.

2. A set, comprising a combination of posts divided transversely by an oblique cut and having registering mortises in the faces 90 of said cut, detachable tongues disposed in said mortises, transverse shoulders on said posts, a cap disposed on and between said posts, braces each having a toe disposed on one of said shoulders and the other toe disposed against said cap, and wedges disposed adjacent the toes of said braces.

3. A set, comprising a combination of posts divided transversely by an oblique cut and having registering mortises in the faces 100 of said cut, detachable tongues disposed in said mortises, bearing lags extending longitudinally of said posts with their upper ends adjacent said cut, a cap disposed on and between said posts, and braces each having a toe 105 disposed upon a lag and the other toe thereof disposed against said cap.

4. A set, comprising a combination of posts divided transversely by an oblique cut and having registering mortises in the faces 110 of said cut, detachable tongues disposed in said mortises, bearing lags extending longitudinally of said posts with their upper ends adjacent said cut, a cap disposed on and between said posts, braces each having a toe disposed upon a lag and the other toe thereof disposed against said cap, and wedges disposed between adjacent toes of said braces.

115 In witness that I claim the foregoing I have hereunto subscribed my name this 10th day of April, 1916.

HOMER M. BARBER.
